CLAIM

The ornamental design for a display panel or portion thereof with a transitional graphical user interface, as shown and described.

DESCRIPTION

FIG. 1 is a front view of a display panel or portion thereof with a graphical user interface showing a first image in a sequence of a design;

FIG. 2 is a front view of a display panel or portion thereof with a graphical user interface showing a second image in the sequence of the design;

FIG. 3 is a front view of a display panel or portion thereof with a graphical user interface showing a third image in the sequence of the design;

FIG. 4 is a front view of a display panel or portion thereof with a graphical user interface showing a fourth image in the sequence of the design;

FIG. 5 is a front view of a display panel or portion thereof with a graphical user interface showing a fifth image in the sequence of the design;

FIG. 6 is a front view of a display panel or portion thereof with a graphical user interface showing a sixth image in the sequence of the design;

FIG. 7 is a front view of a display panel or portion thereof with a graphical user interface showing a seventh image in the sequence of the design;

FIG. 8 is a front view of a display panel or portion thereof with a graphical user interface showing an eighth image in the sequence of the design; and,

FIG. 9 is a front view of a display panel or portion thereof with a graphical user interface showing a ninth image in the sequence of the design.

The appearance of the display panel or portion thereof with graphical user interface sequentially transitions between the images shown in FIGS. 1-9. The process or period in which one image transitions into another forms no part of the claimed design.

The outermost broken-line rectangle illustrates the perimeter of a display panel or portion thereof. The remaining broken
